atmos

UNITED STATES PATENT OFFICE.

ARTHUR M. BURNHAM, OF GARDINER, MAINE, ASSIGNOR OF ONE-HALF TO
CHARLES GIFFORD, OF SAME PLACE.

PAN LIFTER AND TURNER.

SPECIFICATION forming part of Letters Patent No. 372,965, dated November 8, 1887.

Application filed November 18, 1886. Serial No. 219,308. (No model.)

To all whom it may concern:

Be it known that I, ARTHUR M. BURNHAM, a citizen of the United States, residing at Gardiner, in the county of Kennebec and State 5 of Maine, have invented certain new and useful Improvements in Pan Lifters and Turners, of which the following is a specification.

The object of the present invention is to provide a device for lifting pie-plates for either 10 placing them in or removing them from the oven and for turning them around while within the oven, in order to present all sides toward the fire-back, or that side of the oven from which radiates the greatest amount of heat.

15 The invention consists in certain features of novelty, which are hereinafter particularly pointed out in the claims, being first fully described with reference to the accompanying drawings, in which—

20 Figure I is a perspective view of the improved lifter and turner, the positions which the parts occupy while supporting a plate being shown by the full lines and the positions to which they are brought preparatory to 25 grasping a plate being shown by dotted lines. Fig. II is a section taken through the axis of the handle. Fig. III is a transverse section of the handle at III III, Fig. II. Fig. IV is a perspective view, in detail, of one of the parts 30 removed.

35 1 represents the handle, one end of which is notched, as at 2, whereby two lugs or gudgeons, 3, are formed, which are perforated to form journal-bearings for a hollow shaft, 4, whose lower end is enlarged laterally into a circular head, 5, and whose upper end is held from displacement by a flange or collar, 6, slipped over its end and secured by upsetting or otherwise.

40 40 7 represents grappling-arms, each of which is suitably hinged at one end to the circular head 6 and formed at the other with a hook, 8, for engaging beneath the rim of the plate. These arms may be variously formed and 45 hinged to the head 6 without departing from the spirit of my invention. The form shown in the drawings is, however, preferred, for the reason that it is simple, effective, and comparatively inexpensive. It consists of a piece 50 of wire of the requisite strength, bent in the middle to form the hook 8, its extremities be-

ing passed through perforations through the enlarged head 5 and bent into ring shape, so as to prevent their displacement and at the same time permit of their free movement. 55

9 is a rod passing through the hollow shaft 4, and provided at its lower extremity with an enlarged head, 10, its upper extremity being connected to one end of a bent lever, 11, which is fulcrumed at about its mid-length to the 60 handle 1. The head 10 is here shown as consisting of a circular disk; but in practice it may be of any desired shape, it simply being necessary that it be of larger area than the head 5, in order that it may have contact with 65 the grappling arms some distance from their hinges for the purpose of spreading them apart, as hereinafter described.

The lever 11 is here shown as formed of a simple piece of wire of the requisite strength, 70 bent at both ends into an eye, (one for embracing the rod 9 and the other for forming a broad bearing for the thumb of the operator,) and secured to the top side of the handle 1 by a staple, 12. 75

The operation of so much of the device as has thus far been described is as follows: The grappling arms being hinged so as to move with great freedom, they will naturally hang down until they bear upon the head 10, thereby drawing the rod 9 down as far as it is permitted to move and elevating the free end of the lever 11. It will of course be understood that the farther the extremities of these grappling-arms fall below the horizontal plane of 85 the head 5 the nearer they will approach each other, and it is this well-known mechanical action which is made use of in grasping the pan. To grasp the pan, the grappling-arms are first spread to their utmost, which is done 90 by simply depressing the free end of the lever 11, whereby the rod 9, with its disk 10, is elevated. While the disk 10 is being elevated it

impinges against the arms 7 and spreads them apart, the positions which the parts will have 95 assumed after this spreader has acted being represented by the dotted lines in Fig. I. The parts are held in these positions by maintaining the pressure upon the free end of the lever 11 until the lifter is placed over the plate which 100 is to be lifted, and in rather close proximity thereto, whereupon the pressure upon the le-

ver 11 is released and the grappling-arms allowed to fall, so that their hooks will fall below the rim of the pan. Then, by lifting up on the handle, they will be drawn into contact, as shown in full lines in Fig. I. In addition to this arrangement for lifting, the device is provided with mechanism whereby the pan may be turned around from time to time without withdrawing it from the oven, in order to present all of its sides toward the "fire-back," or that side of the oven from which radiates the greatest amount of heat. For this purpose a pinion, 13, is secured to the hollow shaft 4 between the gudgeons 3, with which pinion 15 engages a second pinion, 14, secured to the end of a shaft, 15, journaled in the handle 1. The handle is formed in two parts, *a b*, *a* being the handle proper, and *b* a short section at its extremity, constituting, in effect, a knob for turning the shaft 15, to which it is firmly attached and by which it is held in place.

In order to avoid the expense of boring the section *a* of the handle from end to end, I prefer to cut in the under side thereof a groove, 16, which extends to within a short distance of each end, as shown in Fig. II, and from the extremities of this slot to the extremities of the section the latter is perforated by boring, burning, or otherwise. These perforations 30 form ample bearings for the shaft 15, which latter may consist simply of a piece of wire of the requisite strength. Having lifted the pan, as already described, to turn it around, it is simply necessary to turn the knob or short section *b* of the handle, which, acting through the shaft 15 and pinions 13 14, will revolve the hollow shaft 4, to which the grappling-arms are hinged, the pan being of course carried around too.

40 To release the pan, the operation is the reverse of that necessary to pick it up, and will be understood without further description.

Having thus described my invention, the following is what I claim as new therein and 45 desire to secure by Letters Patent:

1. In a pan-lifter, the combination, with the handle and the hinged grappling-arms having hooks and engaging by gravity with the pan, of a head or disk situated between said arms, a lever fulcrumed to the handle, and connection between said lever and head or disk, whereby the said disk may be brought into contact with and spread said arms when elevated, substantially as set forth. 50

2. The combination, with the handle and the grappling-arms, of the hollow shaft having the enlarged head to which said arms are hinged, the disk situated between said arms, the operating-lever pivoted to the handle, and the rod connecting said lever with said disk, 60 substantially as set forth. 55

3. The combination, with the handle 1 and the grappling-arms 7, of the hollow shaft 4, having the enlarged head 5, to which said arms are hinged, the disk 10, situated between 65 said arms, the rod 9, to which said disk is secured, passing through said shaft, the bent lever 11, engaging said rod, and the staple 12, securing said lever to the handle, substantially as set forth. 70

4. The combination, with a pan-lifter, of a rotatable shaft journaled in the handle and gear-wheels connecting said shaft with the pan-lifting mechanism, whereby the latter is revolved, substantially as set forth. 75

5. The combination of the handle 1, having the perforated gudgeons 3 3, the shaft 4, journaled therein, and having the enlarged head 5, the grappling-arms 7, hinged to said head, the pinion 13, secured to said shaft 4 between 80 said gudgeons, the pinion 14, meshing with the pinion 13, and the second operating-shaft, 15 to which said pinion is secured, substantially as set forth. 85

ARTHUR M. BURNHAM.
